MECHANISM FOR INTERMITTENTLY OPERATING A MEMBER OR ELEMENT

George Armstrong Williamson, High Wycombe, and Percy Holmes and James Blackwood, Southall, England, assignors to The Firestone Tire and Rubber Company, Akron, Ohio, a corporation of Ohio

Application May 10, 1934, Serial No. 724,986
In Great Britain May 12, 1933

11 Claims. (Cl. 74—117)

The present invention relates to mechanism for intermittently operating a member or element and has for its chief object to enable the extent of successive intermittent operations of 5 said member or element to be varied as desired.

In machines of the kind in which a web or strip of material is fed step by step past a cutting device which is operated intermittently to sever the material into pieces or sections of pre- 10 determined width or length it is sometimes desirable to be able to vary the feed of the material in such wise that pieces or sections of material of different widths or lengths are delivered continuously from the machine. A more particular 15 object of the present invention therefore is to provide a machine of this kind having improved mechanism whereby cut pieces or sections of different widths or lengths are delivered continuously.

With the above objects in view the present invention broadly stated consists in mechanism for intermittently operating a member or element comprising a reciprocable headpiece for intermittently operating said member and means 25 cooperating with said headpiece for varying the extent of successive intermittent operations of said member or element.

Stated another way the present invention in its broad aspect consists in mechanism for in- 30termittently operating a member or element comprising a headpiece adapted to be reciprocated continuously and to operate the member or element intermittently and cam means co-operating with said headpiece for varying the extent of 35 successive intermittent operations of said member or element during successive reciprocations of said headpiece.

More specifically stated the present invention consists in the combination with a machine of 40 the kind described including cutting mechanism, of a device for feeding material to said cutting mechanism in successive steps, a reciprocatable headpiece for operating said feeding device and means cooperating with said headpiece for vary- 45 ing the extent of the successive operations of said device by said headpiece.

The cam device may be of any appropriate constructional form and may be moved in any convenient manner. For example it may comprise 50 a disc having adjustable pins projecting radially from its periphery and other pins projecting axially from one face thereof one or the other of the former being engaged either directly or indirectly by the headpiece during a part of each 55 of its reciprocating movements to cause opera-

tion of the member or element and one or the other of the latter being engaged by a pawl pivotally mounted upon the headpiece during another part of each of the reciprocating movements thereof to rotate the disc and bring a 5 different radial pin into position to be engaged by the headpiece.

In order that the invention may be more clearly understood and readily carried into effect reference may now be had to the accompanying 10 drawings illustrating the same by way of example as applied to a machine for cutting a web of material transversely—and preferably on the bias—into a number of sections of different width. 15

In the accompanying drawings:—

Fig. 1 is a front elevation of a cutting machine with the improvements of the present invention embodied therein;

Fig. 2 is a side elevational view of the machine 20 shown in Fig. 1;

Fig. 3 is a view showing the improved mechanism independently of the cutting machine;

Fig. 4 is an enlarged view of a part of the mechanism shown in Fig. 3; 25

Fig. 5 is a side elevational view of the mechanism shown in Fig. 4; and

Fig. 6 is a perspective view of a modified form of mechanism according to the present invention. 30

The cutting machine shown in the drawings is in general of conventional form and includes a cutting mechanism and a feeding device whereby the web of material is fed step by step to the cutting mechanism which is operated to cut the web transversely into successive pieces or sections. As the cutting mechanism itself and the feeding device per se form no part of the present invention only so much of said mechanism and device have been shown as is required clearly 35 to set forth the arrangement and operation of the novel mechanism of the present invention. 40

As shown in Figs. 1 and 2 the cutting machine comprises a main frame 1 on which is mounted a raceway 2 which, if desired, may be adjustable 45 as to its inclination with respect to the frame 1. A cutting device 3 is slidably mounted on the raceway 2 and is reciprocated therein by means of conventional driving mechanism 4, said cutting device 3 being so constructed and operated 50 that its movement in one direction constitutes an operative cutting stroke, while its movement in the opposite direction comprises an inoperative movement of recovery during which the web of 55

material 5 is fed forward as hereinafter described to the next cutting position.

As shown the means for feeding the web of material 5 to the cutting device 3 includes a feeding device in the form of a roller 6 journaled on the frame 1 at the upper part thereof, the web 5 passing from a suitable source of supply over the roller 6 and depending therefrom in operative relation to the cutting device 3. Provision is 10 preferably made in the machine for clamping the web of material 5 in position adjacent the cutting device 3 while being cut.

At one end of the roller 6 there is embodied a unidirectional driving means 7—for example 15 pawl and ratchet mechanism of conventional form—so that the roller 6 may be rotated in one direction to feed the web of material by the pinion 8 but remains stationary when the pinion 8 is rotated in the opposite direction.

20 The pinion 8 is adapted to be rotated in both directions by a toothed segment 9 with which it meshes and the toothed segment 9 is actuated by mechanism according to the present invention so that web sections of different widths are obtainable continuously from the machine.

25 Pivotally connected with the toothed segment 9 is one end of a link 10 the other end of which is pivotally connected to a headpiece 11 secured to a rod 12 slidably mounted in suitable brackets 13 and 14 on the frame 1 of the machine. Also secured to the rod 12 at a distance from the aforesaid headpiece 11 is a pin 15 upon which a cam device 16 is rotatably mounted.

30 The cam device 16 may be of any suitable constructional form but may conveniently comprise a disc 17 having a plurality of pins 18 projecting radially from its periphery and adjustable with respect thereto. For example the pins may be adapted to screw into radial holes in the disc 17 and be secured in adjusted position by suitable lock nuts 19. In addition the disc 17 may have a plurality of pins 20—corresponding in number to the radial pins 18—projecting axially from one face 21 thereof and adapted to be engaged at appropriate intervals by a pawl 22 pivotally mounted upon a second headpiece 23 slidable upon the aforesaid rod 12 and adapted to be reciprocated by means of a connecting rod 24 adjustably connected to a crank arm 25 mounted upon a shaft 26 which is adapted to be rotated continuously—for example by a prime mover 27—during operation of the machine. Preferably the pawl 22 is biased in one direction by a spring 28 and if desired a spring pressed plunger 29 may be adapted to cooperate with recesses 30 on the disc 17 to hold it in its various positions.

35 Also secured upon the rod 12 in a suitable position adjacent to the second headpiece 23 is a stop 29a adapted to be engaged by the second headpiece 23 during part of its reciprocation for the purpose of returning the rod 12, the parts carried thereby and the pivoted toothed segment 9 to their initial positions.

40 The operation of the mechanism is as follows:—Assuming the second headpiece 23 and consequently the rod 12 to be in initial position that is to say in a position such that movement of the rod 12 will cause movement of the toothed segment 9 to rotate the roller 6 clockwise, rotation of the shaft 26 and crank arm 25 will cause 45 the second headpiece 23 to slide upon the rod 12 until it engages with one of the radial pins 18 projecting from the disc 17 of the cam device 16 when the rod 12 and all parts secured thereto, i. e. disc 17, headpiece 11 and link 10 will be

5 moved bodily with the result that the toothed segment 9 will rock about its pivot. The effect of this is to cause the pinion 8 meshing with the segment 9 to rotate and as the pinion 8 is adapted at this time to be clutched to the roller 6 through the aforesaid one way driving connection 7 the roller 6 is rotated to feed the web of material 5 passing over it a predetermined distance. When the second headpiece 23 reaches the limit of its reciprocating movement in one direction the feeding movement ceases and the second headpiece 23 thereupon slides upon the rod 12 in the reverse direction during continued movement of the shaft 26 and crank arm 25 the rod 12 being retained in the position which it has reached 10 owing to its having a tight fit in the brackets 13 and 14 provided for it on the frame 1 of the machine.

15 During the ensuing sliding movement of the second headpiece 23 the pawl 22 mounted thereon engages one of the pins 20 projecting axially from the cam disc 17 and causes rotation thereof to bring the next radial pin 18 into position to be engaged by the headpiece 23 in its next reciprocating movement.

20 Towards the end of its sliding movement the second headpiece 23 engages the stop 29a provided upon the rod 12 and positively moves the rod 12 thereby returning the toothed segment 9 to its initial position and setting the mechanism 25 for the next cycle of operations.

25 The radial pins 18 of the cam disc 17 may be adjusted so as to project to variable distances from its periphery and in consequence a plurality of cut web sections of different widths may be obtained continuously from the machine during operation of the prime mover 27. Alternatively by adjusting the radial pins 18 to the same extent cut web sections of constant width may be obtained continuously from the machine.

30 As will be appreciated the form of the cam device 16 may be varied—for example it may be in the form of an ordinary cam and instead of the axial pins 20 a ratchet device may project from one face of the cam disc 17.

35 In the modified form of apparatus according to the invention shown in Fig. 6 a headpiece 31 and a cam device 32 similar to the cam device 16 previously described may be mounted upon a bracket 33 secured to a slidable rod 34 similar to the rod 12 mounted upon the frame of the machine. In this form of the invention the headpiece 31 is slidably mounted in the bracket 33 and is provided with teeth 35 which mesh with teeth 36 on a second toothed segment 37 pivotally mounted at 38 upon a lateral projection 39 from the bracket 33. Also mounted upon the projection 39 from the bracket 33 in an appropriate position is the cam device 32 which as before mentioned is similar to the cam device 16 previously described and has a ratchet 40 adapted to be engaged by a pawl 41 pivotally connected with the second segment 37 for the purpose of rotating the cam device 32 to alter the feed of the material. In this form of the invention the headpiece 31 is connected by a connecting rod 43 to a crank arm mounted upon a shaft driven by a prime mover similar to the shaft 26 and crank arm 25 of the arrangement shown in Figs. 1-5 and movement thereof from normal position by 45 the connecting rod 43 first causes pivotal movement of the toothed segment 37 due to the toothed connection just described and rotation of the cam disc 32 due to engagement of the ratchet 40 by the pawl 41 and then downward movement 50

of the bracket 33 and consequently the return of the mechanism to its initial position. During movement of the second headpiece 31 in the reverse direction the toothed segment 37 is rocked 5 about its pivot 38 until it is prevented from further movement by engagement with one of the pins of the cam device 32 when the bracket 33 is moved upwardly to cause rotation of the roller 6 and feed of the web to the cutting mechanism. 10 If desired in this form of the invention a counterweight may be employed to balance partially the weight of the bracket 33, and a connection for this is shown at 44.

It is to be understood that although the mechanism of the present invention has been described as embodied in a cutting machine it is capable of use in many other kinds of machines.

What we claim is:—

1. Mechanism for intermittently operating a member comprising variable cam means, a support for said variable cam means operatively connected to said member, a reciprocable headpiece adapted to contact with and move said cam means bodily during parts of its reciprocatory movement and means for operating said variable cam means during another part of the reciprocatory movement of the headpiece to vary the part of said cam means contacted by said headpiece.

2. Mechanism for intermittently operating a member comprising a slidable rod, an operative connection between said rod and said member, a disc rotatably secured upon said rod, a plurality of radially adjustable projections on said disc, a headpiece slidably mounted on said rod, means for causing reciprocatory movement of said headpiece, a stop adapted to be contacted by said headpiece during its movement in one direction secured to said rod on the side of the headpiece remote from said disc, and means for rotating said disc during movement of said headpiece in said direction whereby said projections are engaged successively by said headpiece during successive movements thereof in the opposite direction.

3. In mechanism for intermittently operating a member, the combination of variable cam means, a support for said variable cam means operatively connected to said member, a reciprocable headpiece adapted to contact with and move said variable cam means bodily during a part of each of its reciprocatory movements and means for altering the part of said variable cam means contacted by said headpiece.

4. In mechanism for intermittently operating a member, the combination of a rotatable disc, a support for said rotatable disc operatively connecting same to said member, a plurality of projections extending from the periphery of said disc to different extents, a reciprocable headpiece for moving said disc bodily by contact with one of said projections and automatic means for rotating said disc to cause said projections to be engaged in succession by said headpiece during successive reciprocations thereof.

5. In mechanism for intermittently operating a member, the combination of a disc mounted for both bodily movement and rotation on its own axis, a support for said disc operatively connecting same to said member, a plurality of ad-

justable pins projecting radially from the periphery of said disc, a plurality of pins projecting axially from the face of said disc, a reciprocable headpiece adapted to contact with an appropriate one of said radial pins and cause bodily movement of said disc during a part of each of its reciprocatory movements and means including a pawl carried by the headpiece and engaging, preferably under spring bias, one of said axial pins for rotating said disc during another part of each of its reciprocatory movements of the headpiece for varying the radial pin engaged by said headpiece during its subsequent reciprocatory movement.

6. In mechanism for intermittently operating a member, the combination of a toothed wheel, uni-directional driving means between said wheel and said member, a toothed segment meshing with said wheel, a rod slidably mounted on said frame, a link pivotally secured at its opposite ends to said segment and said rod, a variable cam device secured to said rod, a headpiece reciprocable on said rod and adapted to contact with and move said cam and said rod bodily during a part of each of its reciprocatory movements, means for reciprocating said headpiece, and automatic means for varying the part of said cam device contacted by said headpiece during successive reciprocatory movements thereof.

7. A combination as defined in claim 6 including a stop secured to the rod and engaged and moved by the headpiece during each of its reciprocatory movements to return said rod together with the parts connected therewith to normal position.

8. In mechanism for intermittently operating a member, the combination of gear means for conveying feeding movements to said member, a uni-directional driving connection between said member and said gear means, a rod slidably mounted on said frame, a link pivotally secured at its opposite ends to said gear means and said rod respectively, a disc rotatably secured on said rod, projections extending to different radial extents from said disc, a headpiece reciprocable on said rod and adapted to contact with and move said disc bodily during a part of each of its reciprocatory movements, means for continuously reciprocating said headpiece and automatic means for rotating said disc a predetermined distance during each reciprocatory movement of said headpiece so that said projections are engaged in succession by said headpiece.

9. A combination as defined in claim 8 in which the projections are adjustably mounted on the disc so as to enable the extent which they project radially therefrom to be varied.

10. A combination as defined in claim 8 comprising resilient means for retaining the disc in position with any of its radial projections ready to be engaged by the headpiece.

11. A combination as defined in claim 8 in which the automatic means includes a pawl device carried by the headpiece and a plurality of axial projections from the disc whereby said disc is rotated during part of each reciprocatory movement of the headpiece.
